UNITED STATES PATENT OFFICE.

ORAMEL S. BICKFORD, OF GREENFIELD, MASSACHUSETTS, ASSIGNOR TO LUTHER B. WEISSEBOD, OF GREENFIELD, MASSACHUSETTS.

MACHINE FOR SETTING ARTICLES SUCH AS BUTTONS AND THE LIKE.

1,151,998.

Specification of Letters Patent. Patented Aug. 31, 1915.

Application filed June 10, 1912. Serial No. 702,794.

To all whom it may concern:

Be it known that I, ORAMEL S. BICKFORD, a citizen of the United States of America, residing at Greenfield, in the county of 5 Franklin and State of Massachusetts, have invented new and useful Improvements in Machines for Setting Articles Such as Buttons and the like, of which the following is a specification.

10 This invention relates to a machine for automatically feeding a device or devices of one kind to a position where said devices may be fastened to any suitable article and then fastening said devices to said article.

15 Specifically the invention relates to a machine for fastening buttons, each button being made of two parts, into leather or other material.

The object of the invention is to provide 20 a machine which will be automatic in operation and operate efficiently to fasten, or set and fasten, the part or parts of a button or the like into any desired material.

Other objects of the invention will appear in the detailed description and annexed claims.

In the drawings forming part of this application, Figure 1 is a front elevation of the machine with a part shown in section, 30 taken along the line 1—1, of Fig. 2. Fig. 2 is a sectional view along line 2—2, Fig. 1. Fig. 3 is a plan view of the machine. Fig. 4 is a sectional view through the head of the machine showing, on a larger scale than 35 Fig. 2, the arrangement of the operating mechanism. Fig. 5 is a sectional view taken on the line 5—5, Fig. 2. Fig. 6 is a sectional view of the head of the machine with certain parts broken away to best show the 40 mechanism for throwing back the slide carrying the feeding guides. Fig. 7 is a top view with part broken away showing the arrangement of the feed hopper, the exit openings therein, and the brushes coöperating therewith. Fig. 8 is a section of the 45 same taken on line 8—8, Fig. 7. Fig. 9 is a cross sectional view of one of the feed-guides. Fig. 10 is a partial cross sectional view of the fastening heads showing the way 50 in which two coöperating parts of a glove, or other fastening button, are brought together and fixed in a piece of leather. Fig. 11 is a top view of the end of one of the feed guides. Fig. 12 is a view of a modification.

The two parts of a button for a glove or 55 pocket-book fastener are fed one down each of the feeding guides. The top fastening slide or head moves to pick up one piece and the bottom fastening slide or head moves to pick up the other from the guides; then 60 the said heads remain stationary for a short time. When these two parts are held, one by each fastening head, the feed guides move backwardly out of the way, said movement taking place while the heads are stationary, and then the two parts are brought together by further movement of the heads and fastened into a piece of leather, either 65 on a suitable guide-table or placed directly over one part in interlocking relation in a 70 manner to be described in detail.

Referring to Fig. 1, the motor *a* drives the shaft *b* which, in turn, drives the shaft *c* through suitable speed reducing means. A spur gear *z* fast on the latter shaft meshes 75 with, and drives the gear *d* fast on the shaft *m*. Fixed to the face of the gear *d* is a toothed clutch *e*. A casting embodying the brake-disk *o* and the cam *n* is loose on the shaft *m* and contains a spring-pressed dog-latch *f* normally engaging the clutch *e*. An arm *g*, pivoted at *t* on the frame *v*, is spring-pressed radially against the inner face of the brake-disk *o* (see Fig. 2). The front 80 end of the arm *g* is pointed and beveled so that when the brake-disk rotates with the gear *d*, due to the clutch *e*, the radially projecting portion of the latch *f* will be cammed against its spring and cause the latch to 85 disengage the clutch. As long as the arm *g* is normally held by its spring to cause the disengagement of the clutch, the shaft *m* will rotate without turning the cam *n*. When 90 it is desired to rotate the cam *n*, the arm *g* is pulled downwardly into the position 95 shown in Figs. 1 and 2, whereupon the latch *f* engages the clutch *e* and the cam *n* is turned with the shaft *m*. If after the cam *n* starts to rotate, the arm *g* is allowed to 100 go to normal position, the cam will make just one revolution and stop, for the arm *g* will disengage the latch *f* from the clutch *e*, as described. This intermittent rotation of the cam *n* is desired in some cases and is obtained by mechanism to be described. A 105 foot-pedal *y* is fast to the shaft *h* which carries a spring-pressed lever *i* on a plate, as seen in Fig. 2. As the shaft *h* is rocked

clockwise, it rocks a bell-crank lever pivoted at *h* which, in turn, pulls down on a bar 30 connected to the arm *g*. This action lowers the arm *g* to allow the cam *n* to rotate, as 5 described. As the clockwise movement of the foot pedal continues, the lever *i* passes beyond the bell crank lever allowing it to be returned to normal position by the action of the spring 31, as it returned the arm *g* to the 10 normal position. The arm *g*, in the latter position, stops the cam after one revolution. As the foot pedal returns counterclockwise, the spring-pressed lever *i* passes the bell crank without rocking it. A movable frame 15 *q*, pivoted on the fixed frame *v*, is lowered by the rotation of the cam *n* as the latter bears against the engaging portion *s*. A strong spring *p* holds the engaging portion *s* firmly against the cam surface. The latter 20 is designed to lower the frame *q* slowly against the spring and then allow said spring to raise the frame *q* quickly into the position shown in Fig. 2. As the frame is raised quickly to this position, a brake-shoe 25 *r* (see Fig. 1) is forced against the brake-disk *o* to stop the rotation of the cam in the position shown in Fig. 2. Mounted in the frame *q* is a shaft manually turned by adjusting the wheel *x*. The vertical rod *u* is 30 mounted eccentrically on the shaft, as indicated in Fig. 2, so that if the wheel *x* is turned, the rod *u* is raised or lowered with respect to the frame. As the frame *q* is lowered slowly and raised quickly, the rod *u* 35 is given the same movement to operate mechanism and obtain the results hereinafter described.

Referring to Figs. 2 and 4: The parts of a button are held one in the guide 15 and the 40 other in the guide 16. As the sliding heads *F* and *E* approach one another, the button part held by the guide 15 enters the opening in the part *G* and the spring *H* holds said part therein. The part held by the guide 45 16 is picked up by the pin 1 yieldingly mounted on the sliding head *E*. After the two parts of the button have been thus picked up by the sliding heads, the latter stop momentarily in their movement toward 50 each other and the guides 15 and 16 are then moved backwardly leaving the two parts of the button in alignment held by the sliding heads. The latter then continue to approach forcing the lower part of the button 55 through the hole in the leather piece *J* and into the upper part of the button, as shown in Fig. 6. The sliding heads, on continuing to approach each other, force the parts of the button into the interlocking relation in 60 proper position on the leather piece. In this last operation, the pin 1 is forced downwardly against its spring *L*, and any extra force or jar is taken up by this spring and the yielding of the part *K* which has a lower 65 beveled end to force the horizontal part *M*

against its spring which is regulated by the nut *N*. This last described detailed construction is for the purpose of giving a uniform pressure on the button parts when attaching them to leather of varying thicknesses, the spring back of the part *M* being adjusted by the nut *N* to just balance the outward pressure of the leather on the button parts, the result being that if a thicker piece of leather is used, the spring will be 70 closed instead of the leather being cut through by the bur on the edge of the button parts.

Referring further to Figs. 2 and 4: The part *Z*, formed like a bell crank lever, is 80 fixed on the shaft *A* and has a slot with end adjusting stop screws *V*. In this slot a block *U* slides which latter is pinned to one arm of the lower bell crank lever *C* mounted loosely on the shaft *A*. The lever *C* has one arm 85 engaging the sliding head *E*, to give movement thereto, and the other arm is provided with several teeth engaging like teeth in one end of the upper bell crank *D* mounted on the shaft *B*. The bell crank *D* has its other 90 arm engaging the sliding head *F* to impart movement thereto. As the rod *u* is slowly lowered, as previously described, it rocks the bell crank *Z* clockwise from the position shown in Fig. 2 to that shown in Fig. 4. 95 During this movement from the one position to the other of the bell crank *Z*, the block *U* remains in contact with the right-hand end limiting screw *V*, and the bell cranks *C* and *D* move through the same angle as the crank 100 *Z* because of their connections hereinbefore described. This angular movement is sufficient for the sliding heads *E* and *F* to approach and pick up the parts of the buttons. The reason the bell crank *C* moves through 105 the angle stated is because of its operating connection with the spring *R*. When the right-hand limiting screw of the bell crank *Z* moves to the right, the spring *R* is permitted to force the pivoted arms *Q* and *O* 110 downwardly. An arm *T*, fixed to the crank, is mounted in a long slot of the arm *O* and pressed to the upper limit of said slot by the spring *P*. The spring *R*, therefore, turns the crank *C*, when permitted by the clockwise movement of the crank *Z*, through an angle determined by the stop-screw *S*. This angle is fixed so that the resulting movement of the sliding heads will be sufficient to pick up the parts of the button. After the bell 115 crank *C* has moved through this angle, it can not move farther until the continued downward movement of the rod *u* turns the crank *Z* so that the left-hand limiting screw *V* strikes the block *U* and forces the crank *C* 120 and its extension rod *T* to turn against the force of the spring *P*. While the crank *Z* is turning clockwise with the cranks *C* and *D* stationary, and before the screw *V* strikes the block *U* the shaft *A* turns to operate 125

mechanism to throw the guides 15 and 16 back leaving the parts of the button held by the sliding heads.

Referring to Figs. 3 to 6: The guides 15 and 16 lead from the feed hoppers, which are suitably mounted on the sliding plate Y, fixed in proper guides at the top of the machine. This plate is normally pressed forward to the position shown in Fig. 4 by a 5 spring-operated rod 14 mounted in the frame (see Figs. 3 and 6). A long arm X is loosely mounted on the shaft A and at its upper end has a connection with the sliding plate Y to operate the same. At some distance from 10 the shaft A (see Fig. 6) a spring 4 is mounted. An arm 2, fixed to the shaft A, when the latter moves operates the lever 3 to press against the spring 4 and force the arm X to turn clockwise. By this arrangement for a 15 small angle turn of the shaft 4, a large and quick turn is obtained for the arm X which throws the sliding plate Y and with it the feed hoppers and guides 15 and 16, back against the spring-pressed rod 14. The arm 20 2 is so placed on the shaft A that it turns to throw the sliding plate back during the time that the crank Z is turning, and the crank C is standing still after the sliding heads have picked off the parts of the button from 25 the guides. When the guides 15 and 16 are out of alignment with the sliding heads (see Fig. 6), the continued movement of the crank Z will cause the crank C, and thus the two sliding heads, to press the parts of the button 30 together, one on each side of the leather. The cam n then allows the rod u to return quickly to its original and normal position, whereupon the other parts all return to normal position, as shown in Fig. 2. A rod I 35 is pivoted to the main frame to aid in properly placing the leather or other article which is to have the button fastened therein. A spring 17 (see Fig. 3) normally holds the upper end of this rod against a stop-pin 18 40 on the forward end of the sliding head Y. When all of the parts are in normal position, as shown in Fig. 4, the end of the rod I is in alignment with the parts of the button held by the sliding heads. The leather may 45 then be placed with its punched hole where the button is to be fastened, directly under the small ball attached to the lower end of the rod I. As the sliding plate Y moves rearwardly, the pin or stop 18 turns the rod I on its pivot against the action of the spring 17 thus moving the lower end of the rod I forward and up out of the way of the button parts as they are fastened in the leather. If 50 it is not desirable to feed the leather against a stop gage, as shown on the table 5, Fig. 1, or to locate it by means of the ball or guide-rod I, the machine may be arranged so that, instead of its stopping when all the parts have returned to the normal position, as 55 hereinbefore described, the machine will stop 60 at that part of its movement when the sliding heads have just picked up the button parts and the guides have receded. At this point, the lower part of the button will just project up above the surface of the table 5 70 when the leather is placed to position over the lower part of the button by allowing the lower part of the button to project up through the punched hole in the leather. Then a pressure on the treadle starts the 75 machine when the sliding heads merely approach each other to lock the button parts, when the leather is removed and another piece picked up while the machine parts go through their various motions, as before described, and stop again just after the button parts have been picked up. In order to get the operations just described it is only necessary to re-arrange the stopping mechanism, as by changing the position of the latch f 80 85 and re-arranging the operation of the braking mechanism.

The manner in which the parts of the button are fed will now be described: Referring to Figs. 1, 2, 3, 7, 8, 9, 10 and 11, the feed 90 hoppers are carried by inclined extensions of the sliding plate Y, as stated, and rotatably mounted on the shaft 19 (see Fig. 9). Each hopper cylinder is provided with an exterior ratchet with which the holding 95 pawl 11 and driving pawl 12 co-operate. The latter is mounted on an angle arm 13 (see Fig. 3) so that it may be thrown into and out of operative relation to the ratchet. As the hoppers move back with the sliding 100 plate Y, at each operation the pawls 12 rotate the hoppers to stir up their contents. If desired, the bottom of the hoppers may be stationary so that the relative movement of the sides of the hopper and the contents 105 thereof will stir the latter to a considerable extent in order that they may readily leave the openings in the sides. To further stir up the contents of the hopper, a collar holding a series of radially extending brushes 20 110 is fastened to the shaft 19. An extension of the latter (see Fig. 8) has a yoke-shaped arm fastened thereon which, at each to and fro movement of the hopper, reciprocates the brushes because of a stationary pin on the arm or rod 22 extending from the main frame. Around the bottoms of the hoppers, suitably shaped openings are formed 115 to allow the contents to leave the hoppers. Just outside of these openings guards 10 120 are placed. The hoppers are inclined in a manner to allow the parts of the buttons, or other contents, to leave the interior thereof and to slide or roll down guarded by guards 10 until they enter (one following the other) the guides 15 or 16, as the case may be. As a rule the parts enter these guides in the proper position for the sliding heads E and F to operate in fastening them to the leather, but it frequently happens 125 130

that the parts will not feed as well from the hoppers with the proper side up as they will with the reverse side. In such cases, the guide 15 or 16 is given a twist or turn 5 between the hopper and the sliding heads, and the parts are fed from the hopper in the most convenient way after which they are guided to a point where the sliding heads may take them as previously described. This modification is indicated in Fig. 12 by the guide 16'. In Fig. 11 one part of the button is shown ready to be picked up by the sliding head. The spring 25 holds the parts in place. When the 10 guide 15 is thrown back, after the part has entered the hole in the sliding-head (see Fig. 10), the spring 25 is pushed back into the slot 26; but immediately takes its normal position after the one part held by the sliding head passes by the spring. A very thin spring plate 27 is so placed that its edge 15 stops the button part from leaving the guide 15, allowing the lower edge of the button part to slide underneath, and when the sliding head comes down to grasp the top of the button part, this plate 27 remains between the edge of the button and the sliding head until it is drawn back with the guide 15.

While applicant has described a specific 30 machine, in detail, the invention therein may be carried out by other specific constructions; for that reason the invention, broadly, is not limited to the specific machine herein described.

35 What I claim, is:—

1. In a machine of the class described, two reciprocable members, operative means to move said members toward and away from each other, mechanism to automatically render the approaching movement of the members intermittent, and feeding means to feed devices one to each reciprocating member on part of their approaching movement whereby said devices will be forced into 40 interlocking relation on the completion of the approaching movement.

2. In a machine of the class described, two reciprocating members, operative means to move said members toward and away from each other, mechanism to automatically render the approaching movement of the members intermittent, feeding means positioned to normally feed devices one to each reciprocating member as the latter finishes part of 50 its approaching movement, and operative means to move said feeding means out of its normal position as said members finish their approaching movement, all for the purpose described.

60 3. The combination in a machine for setting buttons and the like, of two reciprocable members, operative means for moving said members toward each other to pick up the parts of a button and fasten them therebetween, feeding guides arranged to feed

one button part to each member as it approaches the other, and mechanism to move the feeding guides out of feeding position as the reciprocable members force the two parts of the button into coacting relation, said 70 operative means arranged to thereafter separate the reciprocable members, all for the purpose described.

4. The combination in a machine for setting articles such as buttons, of two members 75 reciprocable to and from abutting position to set said articles, positioning means to position material to receive the articles between said members, feeding devices to feed the articles into alinement with said members, 80 and operative means to automatically move said reciprocable members slowly toward each other and rapidly away from each other.

5. The combination in a machine for setting articles, such as buttons, of a positioning device to fix the material to receive the article, reciprocating members in alinement to set the article in the material, operative mechanism for said reciprocating members 90 arranged to give an intermittent slow approaching and a rapid separating movement thereto, and means associated with said operative mechanism to cause an appreciable temporary stop in the approaching movement of said members, feeding guides to guide and feed said articles into alinement with the reciprocating members in position to be taken and held thereby, and means associated with said operative mechanism to 95 move the feeding guides out of feeding position during the temporary stop of said reciprocating members.

6. The combination in a machine for setting articles, such as buttons, of two reciprocating members having means to hold the articles thereon, operative mechanism to move said members against one another to set the articles in a suitable material held therebetween, said mechanism comprising 105 two connected bell crank levers one connected with one member and one with the other member, an operating rod and means to automatically give said levers a slow movement in one direction, and a rapid movement 110 in the other direction.

7. The combination in a machine for setting articles such as buttons, of two reciprocating members having means to hold the articles thereon, operative mechanism to move said members toward one another to set the articles in a suitable material with an appreciable stop in such movement, feeding guides to guide the articles into the path of the reciprocating members on their approaching movement, and means to move the feeding guides out of feeding position during the stop in said movement, said operative mechanism comprising two connected 120 bell crank levers one operating one reciprocating member.

cating member and one the other, a third bell crank lever fast on the shaft of one of the other levers which latter is loosely mounted on the same shaft, a slot formed in 5 the third lever, a block fast to one of the other levers and adapted to slide in said slot, an operating rod pivoted to the third lever, together with mechanism to give it a slow movement in one direction and a rapid move-
10 ment in the other direction, and spring-operated means to cause the lever with the block to follow the third lever during part

of its slow movement, then hold the block stationary while the slide moves relative thereto, and a yielding connection in said 15 spring-operated means to allow the three bell crank levers to move together during the last part of the said slow movement after the said spring-operated means has ceased to act.

ORAMEL S. BICKFORD.
